DESIGN FOR A TRIPOD HEAD

Byron R. Sparks, Chicago, Ill., assignor to Harry
J. Graw, Chicago, Ill.

Application September 6, 1945, Serial No. 121,861

Term of patent 14 years

(Cl. D57—1)

To all whom it may concern:

Be it known that I, Byron R. Sparks, a citizen of the United States, residing at Chicago, in the county of Cook and State of Illinois, have invented a new, original, and ornamental Design for a Tripod Head, of which the following is a specification, reference being had to the accompanying drawing, forming part thereof, in which,

Fig. 1 is a top plan view of a tripod head showing my new design;

Fig. 2 is a side elevational view thereof; and
Fig. 3 is a front elevational view of the same.
I claim:

The original design for the tripod head, substantially as shown.

BYRON R. SPARKS.
